(57) **CLAIM**

The ornamental design for a bending brake assembly, as shown and described.

DESCRIPTION

FIG. 1 is a side view of a bending brake assembly showing my new design;

FIG. 2 is a top view thereof;

FIG. 3 is a bottom view thereof;

FIG. 4 is a right side view thereof;

FIG. 5 is a left side view thereof;

FIG. 6 is a side view of the bracket forming part of the bending brake assembly of FIG. 1;

FIG. 7 is a top view thereof;

FIG. 8 is a bottom view thereof;

FIG. 9 is a right side view thereof;

FIG. 10 is a left side view thereof;

FIG. 11 is a side view of an interface plate forming part of the bending brake assembly of FIG. 1;

FIG. 12 is a top view thereof;

FIG. 13 is a bottom view thereof;

FIG. 14 is a right side view thereof;

FIG. 15 is a left side view thereof;

FIG. 16 is a side view of an end stop forming part of the bending brake assembly of FIG. 1;

FIG. 17 is a top view thereof;

FIG. 18 is a bottom view thereof;

FIG. 19 is a right side view thereof; and,

FIG. 20 is a left side view thereof.

The different parts of the bending brake assembly are shown separated in FIGS. 6 through 20 for convenience of illustration.
